UNITED STATES PATENT OFFICE.

JOHN CLIFFORD YORDON, OF QUEENS VILLAGE, NEW YORK, ASSIGNOR TO LAMINATED SHIM COMPANY, INC., OF LONG ISLAND CITY, NEW YORK, A CORPORATION OF NEW YORK.

METHOD OF MAKING SHIMS.

Application filed March 19, 1923. Serial No. 625,960.

This invention relates to an improved method of making shims and in particular to shims which are used between the parts of a bearing and which can be reduced in thickness without any inconvenience or a loosening of the other laminæ which form the shim.

A particular object therefore is to produce a shim which can readily be reduced in thickness, which will act as a take up for wear on the shaft and prevent rattling of the bearing parts and which can be manufactured economically and efficiently.

A further object of my invention is to produce a shim, the laminæ of which will hold themselves together without the aid of a binding element such as lead or other malleable metal.

Referring to the drawings wherein one embodiment of my invention is illustrated;

Figure 1 is a top plan view of a shim composed of thin sheets of metal such as brass assembled on the bed of a power press, the pressure exerting head of the press being shown in outline;

Figure 2 is a front elevation of the power press, a part thereof being shown in section to disclose its construction and the relative position of the shim material;

Figure 3 is a view similar to Figure 2 but showing the head of the press at the limit of its downward travel and after it has acted upon the shim material;

Figure 4 is a section taken on the line 4—4 of Figure 3 and shows the press and shim in cross-section;

Figure 5 is a section taken through the shim after it has been finished, the section being taken to include the bolt hole therein; and,

Figure 6 is a front elevation of a press and shim therein similar to that shown in Figure 3 illustrating a modification in which the edges of the shim material at the bolt hole therein are bent downwardly by a projection on the head of the press.

Referring to the drawings in detail, 5 denotes the bed of a power press which supports the shim laminæ 6 upon which the head 7 of the press acts to form the completed shim 8.

The bed of the press has a raised rear portion 9, the forward edge of which is used as a stop against which the shim laminæ abut and are held in proper superposed relation. This raised portion is not as high as the shim

and therefore does not interfere with the 55 operation of the press head 7.

In order to bind the laminæ 6 of the shim together, I provide the press head on its sides with downwardly extending projections 10, the inner lower edges of which are bevelled 60 as at 11. The distance or width of the head between these projections is slightly less than the width of the shim, so that the projections, when the head is moved downwardly, 65 will bend the edges of the laminæ downwardly, the latter projecting over the sides of the press bed sufficiently to allow this.

When the press head has reached the limit of its travel, the laminæ 6 have not only been compressed but while under compression the 70 ends will have been bent down as at 12 so that the edges of each lamina overlap the edges of the lamina directly beneath it, in the manner illustrated, to hold the laminæ together due to the adhesion of the metal and 75 crowding together of the ends into a mass, the metal of the shims being malleable and therefore susceptible to such change under the extreme pressure exerted by the press 80 head.

In Figure 6 I have added an additional step by providing the press head with a cylindrical projection 13 which overlies the bolt hole 14 in the shim laminæ and whose diameter is slightly greater than the diameter of 85 said hole. Therefore, when the projection passes through the hole 14 it also will bend the edges of the laminæ around the hole, downwardly with the same effect as that produced by the projections 10 on the head of 90 the press. In order to permit the bending of the edge of the hole 14 I provide a suitable larger diameter of hole or depression 15 in the bed 5 of the press which allows the projection 13 to pass through the hole 14. 95

The lower surface then of the shim has projecting portions, at its opposite edges and around the hole. This will give the shim a spring like effect when placed between the parts of a bearing, and when the wear occurs 100 on the shaft the shim will tend to keep the parts of the bearing from rattling until the wear is sufficient to make necessary the reduction in thickness of the shim which is accomplished by removing one of the laminæ 105 with a knife-edge.

It is to be understood that I am not confined to the use of any particular metal in

making the shims nor to the particular edges to be bent down.

What I claim is:

1. The herein described method of making shims which consists in providing a plurality of flat superposed sheets of the same size and binding said sheets together by simultaneously bending the edges thereof through an angle of substantially 45 degrees into overlapping relation.
2. The herein described method of making shims which consists in providing a plurality of flat sheets of the same size in super-

posed relation, and binding the sheets together by bending and pressing the opposite edges thereof into overlapping relation simultaneously while the sheets are superposed.

3. The herein described method of making shims which consists in providing a plurality of flat sheets in superposed matched relation said sheets being provided with an opening, and bending the edges of sheets at the openings therein and on the outer edges simultaneously and under pressure.

JOHN CLIFFORD YORDON.
